UNITED STATES PATENT OFFICE.

JOHN KLASNICH, OF UNIVERSAL, INDIANA.

DOOR-SPRING.

1,224,753.

Specification of Letters Patent.

Patented May 1, 1917.

Application filed December 22, 1916. Serial No. 138,417.

To all whom it may concern:

Be it known that I, JOHN KLASNICH, a citizen of the United States, residing at Universal, in the county of Vermilion and 5 State of Indiana, have invented new and useful Improvements in Door-Springs, of which the following is a specification.

This invention relates to builders' hardware, and more especially to door springs; 10 and the object of the same is to produce a lever attachment connecting a hinged door with its frame and including a spring, all parts being so constructed and disposed that the device will swing the door to a closed 15 position or a completely opened position at the will of the user.

To this end the invention consists in a door spring structure of this character such as is more fully described and claimed below and as shown in the accompanying 20 drawing wherein—

Figure 1 is a perspective view of a door equipped with this spring actuator, viewing the latter a little from the under side of the 25 bracket on which it is supported, the door in this instance being closed.

Fig. 2 is an enlarged plan view of the door actuating mechanism, showing the frame and door in dotted lines only and with the 30 latter about half way open.

In the drawings is shown a door D hinged at H within a frame F, as usual, the door being of that class which closes flat into the 35 frame rather than swinging therethrough.

My improved door spring or actuator comprises a bracket 1 substantially L-shaped in edge view and with its upright leaf secured, as at 2, to the door frame and its horizontal leaf outstanding from the frame 40 above the hinge line of the door. Carried by the latter is a guide 3, secured in any suitable manner to the door at a point remote from its hinge line and preferably extending above its upper edge and there

45 provided with an eye 4. The numeral 5 designates a link pivoted at its outer end at 6 to the bracket at a point which is directly opposite the hinge line, but forward of it a slight distance, and pivoted at 7 to the inner end of the link is the inner end of a rod 8 which extends from this point through the eye 4 of the guide 3. On this rod at about its mid length is fixed a collar 9, and coiled on the rod between this collar and the guide is an expansive spring 10. The link, therefore, indirectly pivotally

connects the inner end of the rod with the bracket, and one function of said link is to prevent the rod from binding within the eye of the guide as the door swings to and fro, 60 the link permitting a certain movement of the inner end of the rod so that its axis may always be coincident with that of said eye.

With this construction, as the door is 65 swung open from the position shown in Fig. 1 toward that shown in Fig. 2, the guide causes the rod to turn with it, and the rear end of the rod by reason of its pivotal attachment to the link causes the link also 70 to turn with it, but the link swings around the pivot 6, whereas the door swings around the hinges which are not in line with said pivot, and the result is that the guide is traveling through an arc having a different 75 radius from that inscribed by any point in the rod, as for instance, its collar. Hence the spring 10 is put under pressure which increases as the door swings half way open, beyond which a reversal of the operation 80 takes place and the spring may expand. Therefore, the operator may open this door by grasping a knob and drawing it toward him until the door has passed a position half way open, and then he can move the 85 door a little farther and release it, and my improved spring will cause it to swing completely open and hold it there. So also in closing the door he can swing it a little more than half way shut and release it, and the spring actuator will close it completely 90 and hold it there, whether there is a latch used or not. The parts are of any desired shape, sizes or proportions, and changes in details may be made within the scope of 95 the appended claims.

Means may be provided whereby the door will be cushioned in reaching either extreme of movement, opened or closed, and I have shown these means applied to Fig. 2 only, 100 and therefore said view is to an extent a modification of what is shown in Fig. 1. I desire it understood that this modification or amplification may be used or not as desired. To the outer end of the rod is attached a stop, which in the illustration is shown as a cotter 11 passing through said rod, although any suitable form of stop applied to or formed on the rod would answer. Next inside said stop is located a 110 cushioning spring 12 which is herein shown as a coil surrounding the rod and preferably

of somewhat less strength than the main spring 10; and a washer 13 may be interposed between the stop and the spring and possibly another washer 14 mounted slidably on the rod at the other end of the spring. The length of the latter is such that it does not contact with the guide when the door stands at an intermediate position as shown in Fig. 2, but it is obvious that as the door passes to its closed position as seen in Fig. 1 or when it swings open to a corresponding position at the other side of the hinge H, the movement of the rod through the guide will draw its stop toward the guide until, just before the door reaches its extreme position, the cushioning spring will be put under tension to prevent slamming of the door.

Having thus described the invention, what is claimed as new, is:—

1. The combination with a door hinged in its frame, and a guide on the door remote from its hinge line; of a link, means for

pivotaly supporting the outer end thereof at a point directly forward of the hinge line, a rod pivoted to the other end of the link and extending slidably through said guide, a collar on the rod, and an expansive spring between the collar and the guide.

2. In a door spring, the combination with a bracket adapted for attachment to the frame over the hinge line of the door, and a guide adapted for attachment to the door remote from the hinge line; of a rod slidably mounted through said guide, a link pivotally connected at one end with the rod and at the other end with the bracket, a collar on the rod between the bracket and guide, a stiff expansible spring between the collar and guide, a stop on the outer end of the rod, and a weak expansible spring between said stop and guide.

In testimony whereof I affix my signature.

JOHN KLASNICH.
